UNITED STATES PATENT OFFICE

ROE P. HENDERSON, OF SPRINGFIELD, OHIO, ASSIGNOR TO THE SPRINGFIELD METALLIC CASKET COMPANY, OF SPRINGFIELD, OHIO, A CORPORATION OF OHIO

DESIGN FOR AN EAR FOR A BURIAL-CASKET HANDLE

Application filed July 3, 1930. Serial No. 36,260. Term of patent 14 years.

To all whom it may concern:

Be it known that I, ROE P. HENDERSON, a citizen of the United States, residing at Springfield, in the county of Clark and State of Ohio, have invented a new, original, and ornamental Design for Ears for Burial-Casket Handles, of which the following is a specification, reference being had to the accompanying drawing, forming part thereof.

In the accompanying drawing:

Fig. 1 is a front elevation, Fig. 2 a top plan view and Fig. 3 an end view of the article showing my new design.

I claim:

The ornamental design for an ear for a burial casket handle as shown.

ROE P. HENDERSON.
